UNITED STATES PATENT OFFICE.

JOSEPH HOPKINSON, OF HUDDERSFIELD, ENGLAND, ASSIGNOR TO J.
HOPKINSON & CO., LIMITED, OF SAME PLACE.

STOP-VALVE.

SPECIFICATION forming part of Letters Patent No. 611,484, dated September 27, 1898.

Application filed December 20, 1897. Serial No. 662,670. (No model.)

To all whom it may concern:

Be it known that I, JOSEPH HOPKINSON, engineer, a subject of the Queen of Great Britain, residing at Britannia Works, Hudders-

field, in the county of York, England, have invented certain new and useful Improve-
ments in Stop-Valves, of which the following is a specification, reference being had to the accompanying drawings.

10 This invention relates to stop-valves with removable seats—that is to say, seats formed in a part which is separable from the valve body or casing; and the said invention has for its objects to insure fluid-tight joints be-
15 tween the metal of the removable part and that of the casing and to facilitate the inser-
tion and removal of the valve and seat when necessary. The part in which the valve-seat is formed is a cylindrical frame or cage where-
20 in the valve is inclosed. The upper end of this cage has an annular surface accurately fitted in the neck of the casing immediately below the cover, and its lower end is seated on the diaphragm or part of the casing which
25 separates the inlet and outlet passages. The cage is so constructed as to allow a free pas-
sage of the water or other fluid through it. In valves provided with seats of this kind it is obviously difficult to insure the fluid-tight
30 contact of the metal surfaces at the upper and lower parts of the cylindrical frame or cage. Stop-valves have been made with re-
movable seats which have the cage or frame secured by screw-threads in the neck of the
35 casing. Others have had the cage provided with packing at the upper end so arranged that when the cover is screwed down to se-
cure the seat in its place it presses upon a ring of packing at the said upper end; but
40 these and other arrangements heretofore adopted have not proved satisfactory. I have therefore sought to accomplish the de-
sired result by totally-different means, which will now be described by the aid of the ac-
companying drawings, in which—

Figure 1 is a vertical longitudinal section of a stop-valve. Fig. 2 is a transverse verti-
cal section of the casing, taken on the line 1 1
of Fig. 1. Fig. 3 is an elevation of the cy-
lindrical frame or cage detached. Fig. 4 is a

horizontal section of the same, taken on the line 2 2 of Fig. 3. Fig. 5 is a longitudinal vertical section showing a modification of my invention.

Like letters indicate the same parts through- 55
out the drawings.

The body or casing *a* is constructed of any required material and dimensions and is suitably formed to receive the cage *b*, in the lower or inner end of which the seat *b'* is formed, 60 as above specified. This cage at its upper or outer end is formed with an annular portion *b*², that fits the orifice of the neck *a'* of the casing *a*. In some instances this orifice may be lined with vulcanite or other suitable 65 material. The peculiar formation of these parts is the important feature of my invention, as will be understood from the following description—that is to say, according to this invention I dispense with screw-threads 70 and with packing-boxes or other contrivances which necessitate the attachment of the cage to the casing otherwise than by the simple contact of their surfaces, and by the employ-
ment of taper or conical surfaces at the upper end of the cage, in combination with the lower end thereof seated on the part *a*² of the casing, I avoid the difficulty usually experienced in attempts to obtain fluid-tight 75 joints at two different parts with surfaces at 80 different angles to each other.

In the form of my invention illustrated in Fig. 1 the aforesaid annular portion *b*² of the cage is made taper on its outer and inner peripheries, its largest diameter being at the 85 top and its smallest outside diameter being somewhat larger than the interior of the neck *a'*, so that the entire cage can be readily in-
serted into the casing and withdrawn there-
from when required. The interior of the 90 neck is made taper to receive the exterior surface of the cage, as shown. The inner surface of this annular portion *b*² of the cage *b* is preferably tapered at an angle less than that of the outer surface. The cover *c* of 95 the casing is formed with a central boss *c'*, through which the valve-spindle works and which is made taper to fit the inner taper surface of the annular portion *b*² of the cage. The taper annular portion *b*² of the cage is 100

thus fitted to and between the inner taper surface of the neck of the casing and the outer taper surface of the boss or central portion of the cover. As the result of this construction and arrangement of the parts the cover *c* when screwed down upon the casing will press the lower end of the cage closely and tightly into contact with the surface on which it is seated and will at the same time force the aforesaid conical or taper surfaces into close contact with each other, thereby insuring sound fluid-tight joints at both ends of the cage.

The removal of the seat can be readily effected at any time by lifting or pulling the cage endwise from the casing when the cover *c* is unscrewed. To facilitate its removal, I prefer that the inner surface of the annular portion *b*² of the cage should be tapered at an angle less than that of the outer surface, as above described, as when the surfaces are so formed the cage will come out with the cover when the latter is removed.

I provide the upper end of the cage *b* with a small flange or projection *b*³, under which, if necessary, a chisel or other suitable implement can be applied to facilitate its removal from the casing.

In some instances the annular portion at the upper end of the cage may be made taper on the outer surface only, the cover being arranged to press upon the outer end of the said cage.

According to a modification of my invention I form the taper or inclined surfaces at the upper end of the cage as follows, viz: I form on the upper surface of the recess in the cover of the casing a V-shaped annulus or ring *d*, the apex of which projects into an annular groove between the cage and the casing, as shown in Fig. 5. Therefore when the cover *c* is screwed down upon the neck the result will be the same as that above described—*i.e.*, the endwise pressure will insure

the tightness and soundness of the joint between the seat and the casing at the upper and lower ends of the cage.

What I claim is—

1. In a stop-valve the combination with the valve-cover of a removable seat frame or cage having at its upper end conical surfaces to engage respectively with conical surfaces on the valve-cover and on the valve-casing and having at its lower end a seating-surface to bear against a shoulder on the valve-casing whereby fluid-tight joints are insured at both ends of the cage, substantially as described.

2. In a stop-valve the combination with a cover through which passes the screw-spindle carrying the valve; of an inwardly-projecting conical boss on said cover; of a removable seat frame or cage having two conical surfaces at its upper end, one of which bears against the conical boss on the cover and the other of which bears against a conical surface on the valve-casing, the said cage also having at its lower end a seating-surface to bear against a flange or shoulder on the valve-casing, substantially as described.

3. In a stop-valve the combination with the cover through which passes the screw-spindle carrying the valve, of a removable cage having two conical surfaces at its upper end adapted to engage respectively with a conical boss on the cover and a conical surface on the valve-casing, of a flange (such as *b*³) at the upper end of the cage for enabling the latter to be lifted when desired by a suitable tool, and of a seating-surface at the inner end of said cage to bear against a shoulder on the valve-casing, substantially as described.

In testimony whereof I have hereunto set my hand this 6th day of December, 1897.

JOSEPH HOPKINSON.
